UNITED STATES PATENT OFFICE.

LEON JEAN BROCHE, OF AKRON, OHIO.

DEVICE FOR DISTRIBUTING AND AUTOMATICALLY CONTROLLING THE DELIVERY OF LIQUIDS.

1,293,017.

Specification of Letters Patent.

Patented Feb. 4, 1919.

Application filed December 28, 1917. Serial No. 209,304.

To all whom it may concern:

Be it known that I, LEON JEAN BROCHE, a citizen of France, residing at Akron, in the county of Summit and State of Ohio, 5 have invented new and useful Improvements in Devices for Distributing and Automatically Controlling the Delivery of Liquids, of which the following is a specification.

10 This invention relates to devices for distributing and controlling the flow of liquids and the object of the invention is to provide a device for filling or partially filling a receptacle with a fluid and maintaining the 15 level of the fluid at a certain height and prevent overfilling thereof. The invention is primarily although not necessarily adapted for the filling of receptacles with drinking water such as are used in factories, office 20 buildings and the like and is adapted to fill a receptacle or drinking vessel up to a certain level to prevent the overfilling thereof, means being provided for automatically regulating the height to which the fluid will 25 rise in the vessel or receptacle. The device is also suitable for other uses but the foregoing is believed to be sufficient for the understanding of the invention.

With the foregoing and other objects in 30 view, the invention consists in the novel construction, combination and arrangement of parts constituting the invention to be hereinafter specifically described and illustrated in the accompanying drawing which forms 35 a part hereof wherein is shown the preferred embodiment of the invention, but it is to be understood that changes, variations and modifications can be resorted to which come within the scope of the matter hereinafter 40 claimed.

The drawing presented is a vertical central sectional view of a device embodying the present invention somewhat diagrammatically arranged.

45 The device embodies a storage reservoir 1 into which a liquid is introduced through a feed pipe 2 the flow of which is controlled by means of a valve 3. Connected with the lower end of the reservoir 1 is an outlet 50 pipe 4 communicating with an upwardly-projecting tank 5 and from the lower end of which extends an upwardly-curved discharge pipe 6, the upper end of which is provided with a packing gland 7 in which is

shiftably mounted the short leg of a goose-neck 8, constituting a siphon. Connected near the lower end of the longer leg of the siphon is a vent pipe 8 containing a controlling valve 10 and attached to the upper end of the vent pipe 9 and in open communication therewith is a flexible tube 11 forming a continuation of the vent pipe 9 and from the tube 11 a pipe 12 extends to and connects the upper end of the reservoir 1. By providing the packing gland 7 and for the siphon 8 the latter may be raised or lowered at will so as to accurately position the longer discharge end 13 of the siphon 8.

In practice the lower end 13 of the siphon 8 will be inserted in some receptacle, such 70 as a drinking cup 14.

In operation the reservoir 1 is partially filled with any suitable fluid through the inlet 2 and flows down into the tank 5 and the exhaust 6 and rises to the level of the 75 dotted line 15 which is on the level with the top of the siphon and thereby fills the siphon sufficiently to start the flow of fluid therethrough into the receptacle 14. As soon as the fluid in the receptacle 14 has risen sufficiently to close the lower end 13 of the siphon 8 the passage of air through the vent pipes 9, 11 and 12 into the reservoir is arrested 80 and further flow of fluid through the siphon is interrupted thereby controlling the 85 level of the fluid in the receptacle 14 and this is further controlled by vertically shifting the siphon 8 whenever desired. The filling of the receptacle 14 lowers the level of the fluid in the open tank 5 as indicated in the 90 drawings below the line 15 and as the filling of the receptacle 14 interrupts further flow of fluid from the reservoir 1 into the tank the level thereof remains substantially as indicated. When the receptacle 14 is removed 95 temporarily, such as a drinking glass is removed from the support the vent through the pipes 9, 11 and 12 are opened permitting the fluid to rise to the level of the dotted line 15 thereby refilling the siphon and permitting the flow of fluid through the siphon which will continue until the receptacle 14 is replaced and partially filled to again interrupt the passage of air through the vent. If it is desired at any time the valve 10 in the 100 vent pipe may be closed during a prolonged removal of the receptacle 14 thereby preventing the rise of fluid in the tank 5 suffi-

ciently high to reach the level of the upper portion of the siphon 8 and establish a flow therethrough.

I claim:

- 5 1. A device of the character described comprising a storage reservoir provided with means for introducing a fluid thereto, an outlet pipe therefrom in open communication with an upright tank, said tank pro-
10 vided with a discharge pipe, a goose-neck-siphon having one end inserted in the discharge opening and the other depending below said tank, a vent pipe connected near the lower end of said siphon and further connected with the upper part of said reservoir above the level of the fluid therein.
- 15 2. In a device of the character described,

the combination with a storage reservoir, means to supply a fluid to said reservoir, an outlet to said reservoir the end of which is 23 provided with a packing gland, a tank in open communication with said pipe, a siphon the shorter leg of which is shiftably mounted in said packing gland, a vent pipe connected to and near the extremity of the 25 longer end of said siphon, a valve in said vent pipe, a flexible tube connected with the vent pipe, and a pipe leading from said flexible tube to the upper portion of said storage reservoir above the level of the fluid therein. 30

In testimony whereof I have hereunto set my hand.

LEON JEAN BROCHÉ.
